UNITED STATES PATENT OFFICE.

GEORGE W. CARVER, OF NEW YORK, N. Y., ASSIGNOR TO GREENE,
TWEED & COMPANY, OF NEW YORK, N. Y., A CORPORATION OF
NEW YORK.

LUBRICATOR.

No. 829,096.

Specification of Letters Patent.

Patented Aug. 21, 1906.

Application filed September 14, 1904. Serial No. 224,471.

To all whom it may concern:

Be it known that I, GEORGE W. CARVER, a citizen of the United States, residing at No. 17 Murray street, New York city, New York, have invented certain new and useful Improvements in Lubricators, of which the following is a specification.

My invention is an automatic force-feed lubricator, and while designed particularly for use in connection with automobiles for lubricating the different parts it is not limited in its use to this connection.

The invention consists in the features and combination and arrangement of parts hereinafter described, and particularly pointed out in the claims.

The objects of the invention will appear from the detailed description and from the advantages to be derived by the use of my invention, as will be referred to hereinafter.

In the accompanying drawings, Figure 1 is a longitudinal sectional view, partly in elevation, through the lubricator, showing a group of force-feed devices operated from a single shaft. Fig. 2 is a transverse sectional view, partly in elevation, of the invention with a different form of nozzle from that shown in Fig. 1. Fig. 3 is a plan view of the invention. Fig. 4 is a detail view, partly in elevation and partly in section, showing one form of means for driving the eccentric-shaft. Fig. 5 is a detail view in section of the friction-clutch seen in Fig. 4. Fig. 6 is a view similar to Fig. 2, showing a modified form of adjusting means for altering the stroke of the pump.

In the drawings, 1 is a casing or reservoir for containing the supply of oil which is to be delivered by the force-feed devices to the point of use. This box or casing has bearings at 2, in which is journaled a shaft 3. This shaft in the particular embodiment of my invention shown is employed to operate a plurality of force-feed devices, each of which is intended to deliver its own supply to a certain part of the machine, though it will of course be readily understood that I do not limit myself to any particular number of said devices, there being one or more. Each force-feed device comprises a fixed piston 4, depending from the top plate of the box or reservoir into the oil therein, the said fixed piston being secured in position by screwing its upper end into what I term for convenience a "nozzle" 5, which in turn is held to

the top of the box or reservoir by a nut 5' 55 screwed on the lower end of the nozzle and bearing up against the lower side of the top of the box. The nozzle has a shoulder 6, resting on the top of the reservoir. The fixed piston depends into the reservoir to a point 60 below the middle of the height thereof, and on this fixed piston a cylinder 7 reciprocates. This cylinder at its upper end has a stuffing-box 8, surrounding the fixed piston, and at its lower end is provided with a section 9, 65 screwed therein and having a shoulder 10, fitting against the end of the cylinder proper. This section has its opening or passage of two diameters, the lower portion being of smaller diameter than the upper portion, and 70 at the upper end of each portion a valve-seat is formed for the small and large check-valves 11 and 12. A check-valve 13 is also employed at the lower end of the fixed piston, said valve 13 resting on a seat formed by the 75 ring portion 14, which is screwed into the said fixed piston and provided at its upper end with a seat for the said check-valve. All of the valves mentioned close downwardly upon their seats, and the same is true of a 80 valve 15 at the upper end of the part or tube constituting the fixed piston. All of the valves I prefer to employ in the form of balls, and the upper valve 15 is pressed down against its seat by a spring 16, said valve 15 85 and spring 16 being arranged in the nozzle.

The cylinder at its lower end is provided with a strainer 17, formed of wire-gauze or other suitable material in the form of a cup, fitted over the end of the cylinder and held 90 by a portion of the wall of the strainer fitting in a depression in the side of the cylinder. For operating the cylinder an eccentric 17 is fixed to the shaft to engage with an arm 18, preferably formed integral with the cylinder 95 and extending laterally therefrom, and to also engage with a disk 19, formed or fixed on the end of a screw 20, threaded through an arm 21, formed integral with the cylinder and extending laterally therefrom over the arm 18 100 and in the same vertical plane therewith. The arm 21 is provided with an enlargement extending upwardly therefrom to afford a long bearing for the screw to work through. By turning the screw through the said bearing the disk 19 is adjusted vertically in relation to the eccentric, and as the length of stroke of the cylinder obviously depends 105

upon the distance between the faces of the arm 18 and disk 19, upon which the eccentric works it will be seen that the amount of oil discharged at each stroke of the cylinder may be regulated by simply turning the screw, and thus setting the disk 19 closer to or farther from the arm 18, whereby all of the revolution of the eccentric will be effective or more or less of the same will be ineffective or lost in driving the cylinder. The screw-rod extends up through the top of the reservoir, and for turning it I have provided a finger-piece or button 22, fixed on its upper end. Below this is provided a set-suit 23 of a size to extend out beyond the edge of the finger-piece for convenient manipulation. This set-suit rests on the upper end of a sleeve 23', which surrounds the screw-rod and rests at its lower end upon the enlarged part of the arm 21. This sleeve is not threaded internally and simply serves as a bearing for the set-suit to work against. In place of packing-rings between the cylinder and the fixed piston I prefer to employ annular channels 22', and these in the present construction of my invention I form in the exterior of the fixed piston. These channels serve to break the joint existing along the crevice between the cylinder and the piston and they fill with oil, and thus serve as packing-rings.

In operation the eccentric rotating with the shaft 3 works against the faces of the arm 18 and the disk 19 and reciprocates the cylinder on the fixed piston. This piston is hollow and is in the form of a tube depending within the reservoir, and it provides the initial discharge-passage for the oil forced from the reservoir by the operation of the cylinder, for it will be obvious that upon the downward movement of the cylinder the oil will enter the cylinder-chamber 23', the valves 11 and 12 being free to rise and allow this, and then upon the rise of the cylinder on the piston the valves 11 and 12 will seat themselves, and the oil thus trapped in the cylinder-chamber will be forced up past the valve 13 and into the hollow piston, and in the continued operation of the pump or forcing device the oil will pass by the upper valve 15 and out through the nozzle through a suitable pipe leading to the point of consumption.

As before stated, I employ in connection with the reservoir a plurality of pumps or oil-forcing devices for supplying oil to various parts of the machine, and these pumps are identical in construction and operation to that described above. They are all operated from the one shaft, which is therefore provided with a plurality of eccentrics placed alongside each other on the shaft. The eccentrics are provided with flanges 25 at their sides, which engage cut-out portions in the cylinders of the pumps and serve to hold the pumps against movement laterally or in

the direction of the shaft. These flanges 25 serve also to hold the pumps against movement toward the shaft or in a direction transversely thereof. These flanges, however, may be omitted, as the eccentrics will operate without them. For driving the eccentric-shaft I may employ a friction-clutch driven by an arm or lever 26, to which is adjustably connected a rod 27, operated from any suitable part of the machine. This lever pivots on the eccentric-shaft 3, shown solid in Fig. 4, and it has secured thereto by means of the screw 28 a clutch-block 29, having inclined clutch-faces 30, on which work the clutch-balls or rolls 31. To the shaft is fixed a clutch-shell 29', which surrounds the clutch-block, and the clutch-rolls are interposed between the flange of this shell and the inclined clutch-faces. Springs 32 serve to force the rolls or balls toward the small ends of the cavities or grooves for the ball-clutches. A detent ball or roller is arranged at 33 to prevent retrograde movement of the clutch.

It will be observed that the stroke of the arm or lever 26 may be regulated by changing the connection of the driving-rod from one point to another along the said arm, for which purpose the lever is provided with a series of openings 34, and the drive-rod, whose stroke is constant, may be set at different points along this arm to vary the length of stroke of the lever, and thus the rapidity of stroke of the pump-cylinder may be changed to feed more or less oil. The transmitting mechanism may be arranged either inside or outside the reservoir, the former arrangement presenting the advantage that the parts will be protected from the accumulation of dust.

I do not wish to limit myself to the precise form of transmitting mechanism above described. For instance, instead of using a friction-clutch as the driving means I may employ ratchet mechanism. The drawings show such a mechanism, and this is illustrated as located within the reservoir. In locating this mechanism within the reservoir the drive-shaft is divided, one section having a socket 35, in which fits the end of the other section. The ratchet-wheel is keyed to the hub of one of the eccentrics at 36, and as this eccentric is in turn keyed to the shaft the said shaft will be turned when the ratchet-wheel is moved. The drive-pawl 37 is pivoted to an arm 38, clamped on the outside of the socket 35 of one of the shaft-sections. This section of the shaft extends outside the casing or reservoir and has an arm 26' fixed thereon driven as before described. The top plate of the casing or reservoir is made up of sections, each of which may consist of a thin plate or bar 39, extending transversely across the reservoir and secured in place by screws

40, passing through the plates and into lugs 41, projecting inwardly from the sides of the reservoir.

It will be seen from the above that the apparatus is free from complication of parts, and as contributing largely to that end the straight fixed piston of tubular form depending into the reservoir and the reciprocating cylinder on the said straight piston are elements of importance. The fixed piston forms a straight and uninterrupted passage for the initial outflow of the oil from the reservoir, the said oil passing upwardly from the reservoir through the said piston and immediately into the pipe or conduit leading to the part to be lubricated. This straight construction of the discharge-tube maintains an even pressure on all the valves, as there are no corners for the fluid to press against. Moreover, this straight construction facilitates adjustment and assemblage of the parts. The movement of the cylinder within the reservoir serves to agitate the oil, and this is particularly the case with the strainer, which agitates the oil and keeps the same from thickening or clogging up. Each pump has its own strainer located on the cylinder thereof, and each strainer thus acts as a separate agitator and insures that the oil passing through the said pump is clear and free from thickened portions or foreign substances liable to clog and interfere with the perfect supply of oil to the parts to be lubricated.

One important feature of my invention is that the pump or forcing device comprising the piston-cylinder and its adjusting-stem can be removed as a whole from the reservoir, and where a plurality of pumps are employed, as shown in the illustrated embodiment of my invention, each pump may be removed independently of all the other pumps. This is done simply by loosening the screws holding the particular section of the top plate which carries the said pump and its adjusting mechanism, and by merely moving the pump laterally it may be readily detached from the eccentric and then lifted out of the reservoir and its adjusting-stem and adjustable disk are removed at the same time, all being supported from the same section of the top plate. The whole device may thus be removed and replaced without changing the relative position of the parts, it not being necessary to alter the position of the disk in relation to the eccentric. In replacing the pump or forcing device an operation the reverse of that above described is performed. The removal of the pump may become necessary or desirable for a variety of causes—such, for instance, as cleaning the valves, cleaning the strainer, which may have become filled up or clogged with any foreign substance, or for setting up the stuffing-box or making other adjustments of the parts. The feature which renders the removability of the pump possible consists of

the arrangement of the pump depending or extending on one side of the shaft and having the laterally-extending arms 18 21 and disk 19, removably fitting over the eccentric. Any pump can be removed and replaced while the apparatus is in full operation. Each pump has its adjustment independent of all the other pumps, though all of the pumps are driven from the same shaft. Each adjustment comprises a part of the driving means for operating the said pump. The adjusting-stems rise through the top plate of the casing and work loosely therethrough, the sleeves before mentioned being smooth on their exterior and moving through openings in the said top plate. As the eccentrics operate the pumps the adjusting-stems move up and down through the top plate, and thus they show the amount of throw that each cylinder has according to the particular adjustment of the parts of each pump. The vertically-movable stems thus serve as indicating means; whereby the operator can tell approximately how much oil is being forced from the reservoir through each pump, and he can then make adjustment of the pumps individually as may be required. Each valve-seat of any one of the pumps is freely accessible by removing certain of the parts. This applies to the upper valve as well as to the two lower valves. Any oil that should work up through the stuffing-boxes of the pumps returns to the reservoir, as all the working parts of the pumps proper are in the reservoir. This return of the oil is due also to the fact that the cylinders reciprocate entirely within the reservoir and no part thereof extends outside.

Instead of using a solid screw-stem, as above described, I may employ the arrangement shown in Fig. 6, in which the screw-stem, carrying the disk at its lower end for the eccentric to work against, has a reduced extension 42 at its upper end, which enters a socket 43 on the lower end of a stem 44, which passes through the top plate of the apparatus. By turning this upper stem 44 the lower screw-stem will also be operated, and as this is threaded through the arm 21 said stem, with the disk thereon, will be adjusted toward or from the eccentric. The parts may be locked in position by a set-nut 23, resting on top of the reservoir, engaging a threaded portion of the upper stem.

Excepting where it is specifically hereinafter noted in the claims I do not wish to limit all the features of my invention to the vertical arrangement of the pump within the reservoir, as other arrangements may be used without departing from some of the features of my invention. Instead of driving the shaft as above described it may be driven by worm-gearing from a belt or sprocket-wheel.

The connection between the pump and its operating means may be said to be a loose

one, in that the pump may be disconnected therefrom by a lateral movement of the pump in relation to its operating means and without requiring any joints being loosened or disconnected within the reservoir.

It will be understood that where in the following claims I employ the term "eccentric" I do so in a generic sense to cover an eccentric or any equivalent device which will accomplish substantially the same result.

I claim—

1. In combination in a force-feed lubricator, a reservoir, a hollow piston-rod within the same and serving as a discharge-pipe for the oil, a cylinder having a valve and working on the outer side of the discharge-pipe, and within the reservoir, and means also located within the reservoir for operating the cylinder, substantially as described.
2. In combination in a force-feed lubricator, a plurality of pumps consisting each of a fixed hollow piston-rod and a cylinder on the outer side of the same, a reservoir comprising an oil-chamber common to all of the pumps and in which said pumps are located, and means for operating the pumps consisting of a shaft and a plurality of eccentrics within the said chamber, and having connection with the cylinders of the pumps, substantially as described.
3. In combination in a force-feed lubricator, a reservoir, a pump comprising a hollow piston-rod depending into the reservoir and serving as an initial discharge-conduit, a cylinder working on the piston-rod, and driving means for the cylinder with which the said cylinder may be engaged and disengaged, said pump being removable through the top of the reservoir, substantially as described.
4. In combination in a force-feed lubricator, a reservoir, a pump depending from the top plate into the said reservoir, and comprising a fixed hollow piston serving as an initial discharge-pipe, means for operating the pump, and means for adjusting the stroke of the pump, said depending pump with its adjusting means being detachable from the operating means, and removable as one body through the upper part of the reservoir, substantially as described.
5. In combination in a force-feed lubricator, a reservoir, a pump depending into the same, means within the reservoir for operating the pump, and a device for adjusting the stroke of the pump, said pump with its adjusting device being detachable from said operating means by a lateral movement of said parts as a whole and being also removable as a whole through the top of the reservoir, substantially as described.
6. In combination in a force-feed lubricator, driving means, a reservoir, and a pump depending into the same and consisting of a movable part having connections extending to one side of the vertical plane thereof for

connection with the driving means, said driving means being also located within the reservoir and from which the pump is disengaged by a lateral movement of said pump, substantially as described.

7. In combination in a force-feed lubricator, a reservoir, a hollow piston-rod extending into the same, a cylinder to reciprocate on the hollow piston-rod, and a shaft within the reservoir, there being a connection extending from one side of the cylinder and operated from the said shaft, substantially as described.

8. In combination in a force-feed lubricator, a reservoir, a drive-shaft therein, and a pump extending into the reservoir on one side of the shaft and having a laterally-extending connection with said shaft adapted to be engaged and disengaged therefrom by a lateral movement of the pump in relation to the shaft, substantially as described.

9. In combination in a force-feed lubricator, a reservoir, a drive-shaft therein, an eccentric thereon, and a pump comprising a hollow piston depending into the reservoir, and a cylinder movable on the outside of the piston, and having means extending laterally therefrom to engage the eccentric, said pump being detachable from the eccentric by a lateral movement and withdrawn from the reservoir by an upward movement, substantially as described.

10. In combination in a force-feed lubricator, a reservoir, a drive-shaft therein, an eccentric thereon, and a pump comprising a hollow piston depending into the reservoir, and a cylinder movable on the outside of the piston, and having means extending laterally therefrom to engage the eccentric, said means comprising a movable part to bear on the eccentric, and means for adjusting the same, said pump with its adjusting means being detachable from the eccentric by a lateral movement and removable as a whole from the reservoir without disturbing the adjustment, substantially as described.

11. In combination in a force-feed lubricator, a reservoir having a top piece or plate, a drive-shaft therein, an eccentric on the drive-shaft, and a pump comprising a hollow piston attached to the top plate and depending therefrom, and a cylinder movable on the outer side of the said piston and having means made up of a fixed arm and a movable bearing-piece for the eccentric to work against and an adjusting-stem for the said movable bearing-piece extending through the top plate, said pump being detachable from the eccentric by a lateral movement and being removable together with its adjusting means and top plate as one body, substantially as described.

12. In combination in a force-feed lubricator, a reservoir, a top piece therefor, a pump depending from said top piece and comprising

5 a fixed piston and a movable cylinder, a shaft having an eccentric within the reservoir, and means on the cylinder engaging the eccentric and comprising an adjustable part, and an 5 adjusting-stem connected with said adjustable part and movable through the top piece to indicate the stroke of the pump, substantially as described.

13. In combination in a force-feed lubricator, a reservoir, a pump arranged within the reservoir and consisting of a piston and a cylinder movable thereon, and a strainer connected with the cylinder to move therewith and agitate the oil, substantially as described. 15

14. In combination in a force-feed lubricator, a reservoir, a fixed piston depending into the reservoir and having a passage extending vertically for the discharge of the oil, a cylinder sliding on the outer side of the lower end of the piston, a strainer provided on the lower end of the cylinder, and valves within the cylinder and hollow piston, substantially as described. 20

25 15. In combination in a force-feed lubricator, a reservoir, a pump arranged therein and comprising a reciprocating part, means for operating the same, and a strainer connected with the reciprocating part to move there- 30 with, substantially as described.

16. In combination in a force-feed lubricator, a reservoir having a sectional top plate, a plurality of pumps supported independently upon a plurality of said sections, and means 35 for operating the pumps, said means being located within the reservoir, and the pumps being independently detachable from the said operating means and independently removable together with the attached section 40 of the top from the said reservoir, substantially as described.

17. In combination in a force-feed lubricator, a reservoir, a plurality of pumps extending into the reservoir, means for driving the 45 pumps, and devices for adjusting the throw of the pumps, each pump together with its adjusting device being removable as one body from the reservoir and the driving means independently of the other pump or pumps with 50 their adjusting devices, substantially as described.

18. In combination in a force-feed lubricator, a reservoir having a sectional top, a shaft within the reservoir, eccentrics thereon, a 55 plurality of pumps each having a connection with one of the eccentrics and adapted to be disengaged therefrom independently of the other pumps, and devices for the pumps to alter the stroke thereof, each pump with its 60 adjusting device being carried by one of the sections of the top of the reservoir, and removable therewith, substantially as described.

19. In combination in a force-feed lubricator, a reservoir, a plurality of pumps extend-

ing therein, a single shaft within the reservoir and means thereon for operating the pumps, each pump having its own adjusting means for altering its stroke independently of the other pumps, and each adjusting means comprising a stem extending from the operating means to a point outside the reservoir, substantially as described. 70

20. In combination in a force-feed lubricator, a reservoir, and a plurality of pumps extending therein and each comprising a movable part, each movable part having its own strainer associated therewith, substantially as described. 75

21. In combination in apparatus of the 80 class described, the piston having the channels around the same, a cylinder working over the said channels which are free for the reception of oil, and valve means, substantially as described. 85

22. In combination in apparatus of the class described, a reservoir, a shaft therein, an eccentric on the shaft, flanges adjacent the eccentric, and a pump extending into the reservoir and engaged by the said flanges to 90 be thereby held in position, substantially as described.

23. In combination, the reservoir, the pump comprising the piston and the cylinder, means for reciprocating the cylinder, and a 95 strainer on the end of the cylinder held by a portion thereof indented into a recess in the side of the cylinder, substantially as described.

24. In combination in a lubricator, a reservoir having a top plate or cover composed of sections, a plurality of pumps associated with said sections of the cover, and means within the reservoir for operating the pumps, said pumps each being detachable from the said 100 means to be removed from the reservoir independently of the other pumps and their cover-sections, substantially as described. 105

25. In combination, in a force-feed lubricator, a reservoir, a plurality of pumps arranged therein, and means for operating the said pumps also arranged within the reservoir, each of said pumps being removable independently of the other pump or pumps by having a part loosely engaging the operating 110 means to be detached by lateral displacement, substantially as described.

26. In a force-feed lubricator, the combination with a reservoir, of a pump comprising two elements within the reservoir, one a cylinder and the other a piston, one of such elements being movable relatively to the other, and actuating means for the relatively movable element, said means being also within the reservoir and said relatively movable element being detachable from the actuating means, substantially as described. 120

27. In a force-feed lubricator, the combination with a closed reservoir, and actuating means within the reservoir, of a pump com- 125

- prising two elements within the reservoir, one a cylinder, and the other a piston, one of such elements being movable relatively to the other and being detachably connected within the reservoir to the actuating means, and adjusting means for altering the stroke of the relatively movable element, said adjusting means comprising a part extending to a point outside of the reservoir, substantially as described.
28. In a force-feed lubricator, the combination with a closed reservoir, and actuating means within the reservoir, of a pump comprising two elements within the reservoir, one a cylinder and the other a piston, one of such elements being movable relatively to the other and being connected to the actuating means within the reservoir and being detachable from said actuating means by a lateral movement, substantially as described.
29. In a force-feed lubricator, the combination with a reservoir, and actuating means

within the reservoir, of a plurality of pumps within the reservoir and each comprising two elements one a cylinder, and the other a piston, one of such elements of each pump being movable relatively to the other element of said pump, and each of said relatively movable elements being connected to the actuating means independently of the other relatively movable elements and being detachable from said actuating means by a lateral movement and independently-operating adjusting means for the relatively movable elements of the pumps for altering the strokes thereof, said adjusting means comprising parts extending to a point outside of the reservoir, substantially as described.

In testimony whereof I affix my signature in presence of two witnesses.

GEORGE W. CARVEL.
